HUMIDIFIER

Leroy W. Hoyt, Stamford, Conn.

Application January 12, 1933, Serial No. 651,252

10 Claims. (Cl. 261—114)

This invention relates to new and useful improvements in humidifiers, and has for an object to provide a humidifier which is completely automatic in its action and which when once installed will need no further attention.

Another object is to provide a humidifier comprising sections whereby a humidifier of any desired capacity may be readily assembled, it being only necessary to install or add the required number of sections or units to give the proper or desired capacity.

A further object is to provide a humidifier which is insertable into the stack of a furnace or boiler between the adjacent ends of sections of the stack to form a portion of the length of the stack and which humidifier functions chiefly or evaporates water chiefly by heat extracted from the hot gases passing through the stack after leaving the boiler or furnace, and therefore uses what would otherwise be waste heat.

Another object is to provide a humidifier including a series of compartments or receptacles arranged one above the other, means to supply water to the upper of said compartments or receptacles, means whereby as the water reaches the proper level in an upper compartment or receptacle it overflows to the compartment or receptacle next lowermost, and means to automatically shut off the supply of water when the water in the lowermost compartment or receptacle reaches a predetermined level. The water is therefore kept at the proper level in all the compartments or receptacles by a single control means.

An additional object is to provide a humidifier which may be readily installed in various locations on a furnace or boiler stack and which may, if desired, be encased and have conduits attached to it for the purpose of conveying moist air to distant rooms or locations.

A further object is to provide a humidifier having the characteristics indicated and which may be easily and quickly set up ready for use and in which any desired number of similar sections may be easily and quickly assembled whereby to provide a humidifier of large or small capacity.

Other objects and advantages will become apparent from a consideration of the following detailed description taken in connection with the accompanying drawings wherein a satisfactory embodiment of the invention is shown. However, it will be understood that the invention is not limited to the details disclosed but includes all such variations and modifications as fall within

the spirit of the invention and the scope of the appended claims.

In the drawings:

Fig. 1 is a plan view of the improved humidifier, parts of the upper section thereof being broken away;

Fig. 2 is a side elevational view of the same, parts being broken away;

Fig. 3 is a vertical sectional view taken substantially along the line 3—3 of Fig. 1;

Fig. 4 is a detail sectional view through a float controlled valve means, the view being taken substantially along the line 4—4 of Fig. 1;

Fig. 5 is a plan view of a portion of the lower or first section of the humidifier;

Figs. 6, 7 and 8 are elevational views showing various installations of the humidifier; and

Fig. 9 is a view partly in side elevation and partly in section showing the humidifier encased and connected with conduits for conveying air to the humidifier and for conveying moistened air from it.

Referring in detail to the drawings, the improved humidifier as here disclosed is made up of four sections including a bottom section 10 and upper sections 11, 12 and 13. As the description proceeds it will become evident that in any installation a bottom section 10 must be employed and that such section might in fact be used alone and form a humidifier of considerable capacity. The sections 11, 12 and 13 are duplicates of one another and any desired number of said sections might be employed depending on the amount of moisture desired.

Each of the sections is in the form of an annular receptacle and each includes a bottom wall 14, an inner wall 15 and an outer wall 16. On their lower surfaces each bottom wall is provided adjacent its outer edge with an annular bead or rib 17, the said bead or rib being spaced inwardly of the outer surface of wall 16 a distance which is the thickness of said wall. The upper edge of the outer wall 16 of each section or receptacle is notched to provide upstanding lugs or projections 18 and openings 19 between such lugs or projections. Each section has its inner wall of greater height than its outer wall and each inner wall is constructed with an offset intermediate its upper and lower edges whereby inner and outer annular shoulders 20 and 21 respectively are provided.

The relationship of the various parts is such that the sections may be assembled and supported one on the other in stacked relation. Further, owing to the structure described a humidifier

fier including the desired number of these sections may be conveniently mounted in a stack between the adjacent ends of sections of the stack the humidifier when thus mounted forming a portion of the length of the stack. In assembling the humidifier between the adjacent ends of the sections 22 and 23 of the stack the lower section 10 of the humidifier is mounted on the upper end portion of the lower stack section 22. The relationship is such that the upper end of stack piece or section 22 engages the lower outer shoulder 21 of humidifier section 10 and the upper end portion of said stack section is embraced by the portion of inner wall 15 below said shoulder 21. This is as clearly shown in Fig. 3.

Next, the humidifier section 11 is to be added and it is simply disposed on the section 10 with its bead or rib 17 arranged at the inner sides of the upstanding projections or lugs 18 of section 10 and with its shoulder 21 resting on the upper edge of the inner wall 15 of section 10. The upper end portion of this inner wall of section 10 is embraced by that portion of the inner wall of section 11 below the shoulder 21 of said section 11. Section 12 is disposed on section 11 in the same manner in which section 11 was disposed on section 10 and the operation is repeated in connection with section 13 and with as many additional sections as required.

When the last section is in place the upper section 23 of the stack is slipped into place and its lower end engages the inner shoulder 20 of the last applied section which in the drawings is the section 13. Further, the inner surface of the lower end portion of the stack section 23 may closely embrace the upper end portion of the inner wall 15 of the last applied humidifier section. With this arrangement it will be noted that each added humidifier section is supported by the previously mounted humidifier section and that the various sections of the humidifier each form a portion of the stack into which they are introduced and that the upper stack section is supported against the last added humidifier section.

Each humidifier section is open at its upper side and the notches or openings 19 in the upper edges of the outer walls of the sections provide openings whereby air may circulate between the sections and over their open upper sides. Projecting inwardly from the inner wall of each section are a plurality of ribs or fins 24 which ribs or fins may or may not be in vertical alignment when the sections are assembled. As will later be described, water is supplied to the various receptacles comprising the sections of the humidifier and it will be appreciated that the ribs or fins 24 of the various sections extend into the stack opening so that the hot gases passing through the stack will engage and heat the fins. This heat will be conducted by the fins to the inner walls of the various humidifier sections and such walls themselves be additionally heated by the hot gases contacting with them. The heat will, of course, be transmitted to the water in the various sections or receptacles with the result that the water will be rapidly evaporated thus adding considerable moisture to the atmosphere.

The various sections or receptacles 10 through 13 may be divided into compartments 26 as by means of radially extending walls or ribs 25 extending between the inner and outer walls 15 and 16 of the sections. These dividing or partitioning walls 25 will, of course, conduct heat from the inner walls of the receptacle to the water in the receptacle thereby further heating the water to

increase evaporation. In its bottom wall 14 in each of its compartments 26 each humidifier section (with the exception of the first or bottom humidifier section 10) is provided with an opening 27 which may be elongated as shown and about each such opening there is provided an upstanding flange or wall 28 each such flange or wall being somewhat greater in height than are the partitioning or dividing walls 25 forming the compartments.

The openings 27 together with the upstanding flanges or walls 28 provide overflows, the function of which will later more fully appear. Here, however, it is pointed out that while such walls or flanges 28 extend above the radial partitioning or dividing walls 25 they are not as high as the upper edges of either the inner or outer side walls of the various sections 10 through 13. Certain of the radially extending partitioning walls 25 may be provided with enlargements 29 having openings therethrough for the passage of bolts.

Also, enlargements 30 may be formed between the inner walls 15 of the various sections and the various upstanding flanges or walls 28 forming the overflows. These latter enlargements 30 are also provided with vertical openings and when the various sections are assembled to form the humidifier certain of the openings are brought into registry and bolts 31 may be passed through them and the nuts on the ends of such bolts may be tightened to draw the sections against one another and secure them in their proper assembled relationship. When the sections are assembled they are so arranged relatively that the openings 27 in the bottom of each section is out of registry with the openings in the bottom wall of the next adjacent section.

The water supply means includes a housing 32 having a thickened wall portion 33 provided with a relatively small water inlet opening 34 and a valve 35 arranged when seated to close said water inlet. A supply pipe 36 connected with any suitable source of supply is arranged to deliver water to the small inlet or passage 34 and when the valve 35 is off its seat water from the supply pipe 36 passes to a pipe or tube 37 which has its upper end portion connected with an L-fitting 37a extending through the outer wall of the uppermost humidifier section whereby to discharge water into such humidifier section.

As the water in the upper humidifier section 13 reaches the upper end of the overflows represented by the openings 27 and the tubular walls 28, the water passes downwardly through such overflows and into the next lower humidifier section, which in the drawings is the section 12. The overflow openings in section 12 are as above stated out of registry with the overflow openings of section 13 and the section 12 will therefore fill. When the water reaches the proper level in section 12 additional water supplied to the section will overflow through the tubular walls 28 of said section and pass to the next lowermost section or to the section 11 as shown in the drawings.

On section 11 becoming sufficiently filled the water overflows to the bottom section 10 and this section through a fitting or nipple 38 communicates with the float chamber of the housing 32 as clearly shown in Fig. 3. When the water in section 10 reaches the desired predetermined level it will have reached this same level in the float chamber of housing 32 with the result that the float 39 in said chamber will be lifted to seat the valve 35 and thereby cut off the further sup-

ply of the water. Nipple 38 communicates directly with but one of the compartments 26 of the lower section 10 and this compartment is designated 26a and as clearly shown in Fig. 5 is provided with a series of radially extending fins 40 formed with the inner walls 15 of the section.

These fins 40 will serve to conduct heat from the inner wall 15 of section 10 outwardly into the compartment 26a of said section. Thus the water 10 in this particular compartment will be evaporated more rapidly than will the water in the other compartments and as soon as the level of the water descends, float 39 will drop and valve 35 will be raised off its seat whereby additional water 15 will be supplied to the uppermost section or receptacle. The water will overflow from one section to the next as above described until the water in compartment 26a reaches the desired level when the valve 35 will again be seated.

From the foregoing it will be understood that the water in the compartment 26a will by its level control the opening and closing of the valve 35. This is true since such compartment is in communication with the float chamber through the 25 nipple or fitting 38 and an increased evaporation or the more rapid rate of evaporation is provided for by the fins 40. Of course, it will be understood that fins corresponding with the fins 40 may, if desired, be provided in each of the compartments 30 of each section. In the event this is done then a greater number of fins should be provided in the compartment 26a since to insure a supply of water in all of the sections the water should preferably be evaporated more rapidly from the 35 control compartment. It will also be noted that these additional fins are necessary in this particular compartment since there is an increased supply of water to be acted on, this increased supply being represented by the water in the 40 float chamber.

The housing 32 may have its upper wall 41 removably secured in place as by screws 42 and in its lower or bottom wall it may be provided with a clean-out opening 43 normally closed as 45 by a plug 44. The overflows of the various sections in addition to providing means whereby a lower section is filled by water overflowing from an upper section, also provides for the circulation 50 of air from one section to the next. Of course, the openings 19 in the upper edge portions of the outer walls of the section provide for the circulation of air between the sections and over their open upper sides. Air may also circulate upwardly through the overflow openings. It is further to be understood that if 55 desired the bottom or initial section of the humidifier may be of the same construction as the upper sections. That is, it may be provided with an overflow and in such instance the float chamber would be so arranged that the float would operate to close the control valve and shut off the supply of water before the water in the lower section reached overflow level.

Figs. 6, 7 and 8 show various installations of the improved humidifier. In Fig. 6 a boiler or furnace is indicated at 45 and is provided centrally with a stack 46 between the adjacent ends of adjacent sections of which the improved humidifier may be inserted as generally suggested at 47. In Fig. 7 the furnace or boiler is designated 48 and has a stack connected with its rear side, the stack including a short rearwardly extending section 49 and a vertically extending section 50 in which is mounted the humidifier generally indicated at 51. The boiler or furnace of

Fig. 8 is generally designated 52 and has connected with it a horizontally extending stack portion 53 into which may be introduced a T-fitting 54 on the vertically extending stem portion of which the humidifier may be mounted as at 55. With this construction a suitable baffle 56 may be introduced to deflect the hot gases upwardly into the humidifier and to prevent the escape of such gases a closure 57 may be applied to the upper end of the fitting or to the upper end of the 10 humidifier.

In Fig. 9 the humidifier generally designated 58 and including the sections 10, 11, 12 and 13 is shown as enclosed in a casing 59 which may be of sheet metal or the like and the upper side or top of the casing is closed as by one of the cover members 57 shown in Fig. 8. Conduits 60 and 61 communicate with the interior of the casing 59 and the conduits 60 may be used for supplying air to the interior of the casing and the conduit 61 may be used to convey the air, moistened by the humidifier, to any desired rooms or other locations. If desired, fans may be introduced to provide forced circulation and the air supplied to the humidifier through conduits 60 may be warm air. A baffle 62 is provided whereby air entering through conduits 60 must pass through the humidifier to reach the exit or discharge conduits 61. The lowermost humidifier section 10 is provided about its upper edge with an inclined annular flange or lip 63 whereby any condensation forming on the interior of the casing 59 will drain into the lower humidifier section. Further, each humidifier section, when encased as in Fig. 9, may on its outer surface be provided with ribs or fins 64 to absorb and conduct heat to the water of the section, when heated air is blown into the casing.

It will now be understood that the humidifier as installed includes a greater or lesser number 40 of sections or units depending on the size of the buildings to be treated. On this basis once the device is installed there is no occasion for regulating it since the float 39 will operate the valve 35 to keep the proper water level in each of 45 the sections of the humidifier. With the humidifier installed on a stack in a basement of a dwelling the moistened air will penetrate to all parts of the dwelling. When the humidifier is encased as in Fig. 9 a forced circulation of air 50 through the humidifier will provide air of the desired humidity to a relatively large structure. As suggested in Figs. 6, 7 and 8 the humidifier may be installed in a number of ways and the invention is not limited to any precise manner of installing the humidifier or to a humidifier of any particular number of sections. As suggested above the lower section 10 of the humidifier need not be structurally different from the other sections although it is preferred that the lower section have an imperforate bottom wall. The moisture given off keeps the floors of the building from drying out, and as this humidifier is placed on the smoke pipe from the heater it is very beneficial. Also, the water absorbs considerable heat and gives it off into the dwelling, which represents a considerable saving as it is waste heat which would otherwise be lost up the chimney.

Having thus set forth the nature of my invention, what I claim is:

1. In a humidifier, a plurality of sections arranged one above the other, each of said sections comprising an annular receptacle the inner wall of which is of a diameter to form a portion of the length of a stack, said sections open at their 75

- upper sides and arranged to have air circulate between them, means for supplying water to the uppermost of said sections; one of said receptacles having fins on its inner wall to extend into a stack to be heated by the gases passing therethrough and conduct such heat to the water in the receptacle, an overflow in each of said upper compartments whereby when the water reaches a predetermined height in an upper compartment it overflows to a lower compartment, said overflow in each compartment arranged out of registry with the overflow of the compartment beneath it, each of said overflows comprising an opening in the bottom wall of the compartment and an upstanding wall about said opening, and means to automatically shut off the supply of water to the uppermost compartment when the water in the lowermost compartment reaches a predetermined level.
2. In a humidifier, a plurality of annular sections, each of said sections comprising a receptacle having inner and outer flanges at its upper edges and inner and outer shoulders at its underside whereby on engaging the respective flanges of one section with the respective shoulders of another section the sections are supported on one another, said sections open at their upper sides, each of said sections having openings through its outer flange whereby to permit of the circulation of air above the section and below the next uppermost section, means for supplying water to the uppermost of said sections, means whereby the overflow from an upper section passes to the next lower section, and means to automatically shut off the supply of water to said uppermost section when the water in the lowermost section reaches a predetermined level.
3. In a humidifier, a plurality of annular receptacles arranged one above the other, a pipe line for supplying water to the uppermost of said receptacles, a valve in said pipe line, a float chamber, a float in said chamber and connected with said valve, means whereby the overflow of water from an upper receptacle passes to the next lower receptacle, means dividing the lowermost of said receptacle to form a compartment therein, means whereby said receptacles are mounted on a stack to have their inner walls heated by gases passing through the stack, fins on the inner wall of the lowermost of said receptacles and extending into said compartment to conduct heat to the water therein, and a passage between the float chamber and the said compartment whereby on the water in said compartment reaching and falling below predetermined levels the said valve is closed and opened.
4. In a humidifier, means providing a plurality of compartments arranged one above the other, means for supplying water to the uppermost of said compartments, means whereby the overflow from an upper compartment passes to the next lower compartment, means to automatically shut off the supply of water to said uppermost compartment when the water in the lowermost compartment reaches a predetermined level, a casing enclosing said humidifier, vertically spaced conduits to conduct air to and from said casing, and a baffle in said casing between said conduits whereby air entering the casing through one conduit must pass through the humidifier to reach the other of said conduits.
5. In a humidifier, a plurality of sections arranged one above the other, each of said sections comprising a receptacle, said sections open at their upper sides and arranged to have air circulate between them, fins on the outer surfaces of said sections, means for supplying water to the uppermost of said compartments, means whereby the overflow from an upper compartment passes to the next lower compartment, means to automatically shut off the supply of water to said uppermost compartment when the water in the lowermost compartment reaches a predetermined level, a casing enclosing said humidifier, vertically spaced conduits conducting air to and from said casing, and a baffle in said casing between said conduits whereby air entering the casing through one conduit must pass through the humidifier to reach the other of said conduits.
6. In a humidifier, a plurality of sections arranged one above the other, each of said sections comprising an annular receptacle the inner wall of which is of a diameter to form a portion of the length of a stack, said sections open at their upper sides and arranged to have air circulate between them, means for supplying water to the uppermost of said sections; one of said receptacles having fins on its inner wall to extend into a stack to be heated by the gases passing therethrough and conduct such heat to the water in the receptacle, an overflow in each of said upper compartments whereby when the water reaches a predetermined height in an upper compartment it overflows to a lower compartment, said overflow in each compartment arranged out of registry with the overflow of the compartment beneath it, each of said overflows comprising an opening in the bottom wall of the compartment and an upstanding wall about said opening.
7. In a humidifier, a plurality of annular sections, each of said sections comprising a receptacle having inner and outer flanges at its upper edges and inner and outer shoulders at its underside whereby on engaging the respective flanges of one section with the respective shoulders of another section the sections are supported on one another, said sections open at their upper sides, each of said sections having openings through its outer flange whereby to permit of the circulation of air above the receptacle and below the next uppermost receptacle, means for supplying water to the uppermost of said sections, and means whereby the overflow from an upper section passes to the next lower section.
8. In a humidifier, means providing a plurality of compartments arranged one above the other, means for supplying water to said compartments, a casing enclosing said humidifier, conduits to conduct air to and from said casing, a baffle in said casing between said conduits whereby air entering the casing through one conduit must pass through the humidifier to reach the other of said conduits, and a flange arranged to conduct condensation from the inner surface of the casing to the lowermost of said compartments.
9. In a humidifier, a plurality of sections arranged one above the other, each of said sections comprising a receptacle, said sections open at their upper sides and arranged to have air circulate between them, means for supplying water to the uppermost of said sections, means whereby the overflow from an upper section passes to the next lower section, means forming a compartment in the lowermost of said sections, means whereby the water will be evaporated most rapidly from said compartment, and means to automatically shut off and start the supply of water to said uppermost section when the water in said compartment reaches predetermined levels.

10. A humidifier section comprising a receptacle having a bottom wall and inner and outer annular side walls extending upwardly from said bottom wall whereby the section may be inserted in a stack with its inner annular side wall forming a portion of the length of the stack, flanges at the upper edges of said side walls, and shoulders

at the under side of said receptacle and spaced apart as are said flanges whereby a plurality of such sections may be supported one on the other by engaging the respective shoulders of one section with the respective flanges of another section. 5

LEROY W. HOYT.
